US0D1110095S

(12) United States Design Patent (10) Patent No.: US D1,110,095 S
(45) Date of Patent: * Jan. 27, 2026

(54) OUTDOOR BARBEQUE GRILL ASSEMBLY

(71) Applicant: Nexgrill Industries, Inc., Chino, CA (US)

(72) Inventors: Sherman Lin, Chino Hills, CA (US); Wilfrido Barajas, Jr., Riverside, CA (US); Andre de Beer, Tustin, CA (US)

(73) Assignee: Nexgrill Industries, Inc., Chino, CA (US)

() Term: 15 Years

(21) Appl. No.: 29/899,631

(22) Filed: Aug. 10, 2023

4,089,258 A 5/1978 Berger
4,277,106 A 7/1981 Sahley
4,321,857 A 3/1982 Best

(57) CLAIM

The ornamental design for an outdoor barbecue grill assembly as shown and described.

DESCRIPTION

FIG. 1 is a perspective view of an outdoor barbecue grill assembly showing our new design;

FIG. 2 is a top plan view thereof;

FIG. 3 is a front elevation view thereof;

FIG. 4 is a left side view thereof;

FIG. 5 is a right side view thereof;

FIG. 6 is a rear elevation view thereof; and,

FIG. 7 is a bottom plan view thereof.

The broken lines in the figures show portions of the outdoor barbecue grill assembly that form no part of the claimed design.

1 Claim, 4 Drawing Sheets
